UNITED STATES PATENT OFFICE.

ANDREW G. ANDERSON, OF JANESVILLE, WISCONSIN.

CULTIVATOR-TOOTH.

SPECIFICATION forming part of Letters Patent No. 315,879, dated April 14, 1885.

Application filed January 21, 1885. (No model.)

To all whom it may concern:

Be it known that I, ANDREW G. ANDERSON, of Janesville, in the county of Rock and State of Wisconsin, have invented certain new and useful Improvements in Cultivator-Teeth; and I do hereby declare the following to be a full, clear, and exact description of the invention, such as will enable others skilled in the art to which it appertains to make and use the same.

My invention relates to an improvement in teeth for cultivators, seeding-machines, harrows, &c., and relates particularly to that class of teeth which are constructed to yield and pass over obstructions encountered in the operation of the machine.

The object of the invention is to provide a tooth with a yielding spring-connection with the drag-bar, the parts to be constructed in such a manner that they may be adjusted to retain the tooth against any predetermined strain exerted on its lower or working portion, whereby it shall be adapted for use in different kinds of soil, and which will allow it to slip or yield to any obstruction or strain, and thus obviate breakage or injury to its parts, the spring-connection to be arranged so as to return the tooth to its normal and operative position when it has passed over an obstruction or has been released from undue strain; further, to construct and arrange the connecting and yielding mechanism in such a manner that the tooth will withstand the greatest strain while in its normal or operative position, and when once forced rearwardly from such position or adjustment it will readily yield to such an angle as to allow it to pass over an obstruction.

With these ends in view my invention consists in certain features of construction and combinations of parts, as will be hereinafter described, and pointed out in the claims.

In the accompanying drawings, Figure 1 is a view in side elevation of a drag-bar having one of my improved tooth attachments connected therewith. Fig. 2 is a similar view showing one side of the drag-bar removed, the tooth being represented in its normal or operative position. Fig. 3 is a similar view showing the tooth in its position to pass over an obstruction. Fig. 4 is a plan view, and Fig. 5 is a vertical section.

A represents a drag-bar, preferably constructed of the wrought-iron bars *a a*, diverging at their forward ends, and perforated for their pivotal attachment to the cultivator-frame. The bars *a a* are secured together near their forward ends by means of the rivets *b b*, (one or any number may be employed,) which are preferably constructed of wrought-iron, and each formed with a central enlarged collet, *b'*. The collets or disks *b'* serve as spacing-disks and present enlarged bearings, thereby serving to insure a strong and firm connection for the side pieces of the drag-bar.

B represents the cultivator-tooth, which may be of any approved construction. The tooth is pivoted by the bolt *c* between the rear ends of the link-bars *C C'*, the forward ends of the latter being pivoted on a bolt, *c'*, extending through the side pieces of the drag-bar. Between the side pieces of the drag-bar at its rear end are pivoted on the bolt *D* the plates or bars *E E*. The upper end of the shank of the tooth is pivoted between the rear arms, *e*, of the bars *E E* on the bolt *E'*, while on a bolt, *F*, passing through their forward arms, *f f*, is pivoted one end of a volute spring, *G*, which extends upwardly above the drag-bar, and curves forwardly and downwardly between the side pieces of the drag-bar, and then extends upwardly between the bars *E E*, the rear end, *H*, or heel of the spring being constructed in the form of a fork, which engages the eccentric block or roller *I*, mounted on a bolt, *J*, extending through the rear end of the drag-bar. This roller is mounted eccentrically and in rotary adjustment on the bolt, and is constructed with an annular groove, *i*, in which rests the forked end of the spring *G*. The upper end of the tooth *B* rests normally in contact with the face of the eccentric roller *I*, or against the spring lying on the face of the roller, the tooth being held in this position by the tension of the spring *G*. The several adjustments of the eccentric roller *I* will therefore determine the vertical adjustment of the tooth with respect to the drag-bar or line of draft, and hence determine the degree of resistance which the point of the tooth will require to throw it back. For example, let *x x* represent a line drawn parallel with the drag-bar through the pivotal bolt *D*, and let *y y* represent a line drawn through the same

bolt parallel with the bars E E. Now, when the side of the eccentric which is the least distance from the axial bolt J is toward the end of the tooth B the angle $x D y$ will be the least, and the amount of resistance required to upset the tooth will consequently be the greatest; but when the side of the eccentric roller which is greatest from the axial bolt J is toward the end of the tooth the angle $x D y$ will be the greatest, and the amount of resistance required to upset the tooth the least. Again, by means of the rotary adjustment of the eccentric roller the volute spring may be either contracted or expanded, and hence its tension increased or decreased as desired.

If the character of the work to be done is such that it is desirable that the tooth shall yield to the minimum strain exerted on its point, the eccentric roller is adjusted so that the tooth B shall occupy a depressed position with reference to the drag-bar—that is, so that the angle $x D y$ shall be the greatest, and so that the spring will be allowed to expand as much as possible—while, on the other hand, if the cultivator is to be used in very stiff soil, and it is desired to retain the teeth against maximum strain, then the eccentric roller is adjusted so as to make the angle $x D y$ as small as possible, and so as to contract the spring to its fullest extent.

In the operation of the tooth, power is transmitted from the drag-bar to the tooth through the links C C', the tooth being prevented from turning on its pivotal bearing c by means of the locking-bars E E, which are retained in the position illustrated in Fig. 2 by means of the tension of the spring G, which is constantly exerted to depress the forward arms, f f, of the locking-bars. When the tooth is in this its normal position for work, the bolt E', which serves as a pivotal connection between the upper end of the tooth and locking-bars E E, is nearly in a horizontal plane with the bolt D on which the locking-bars E E are pivoted, and hence the tooth may be subjected to great strain while in this position without its being rotated on its bearing; but should the tooth meet with an obstruction which would be liable to break it, unless released from the undue strain caused thereby, the lower end of the tooth will be retained in a stationary position, while its upper end will be carried along with the drag-bar, the locking-bars being rotated on their bearing enabling the tooth to assume the position illustrated in Fig. 3, and thus pass over the obstruction. When the tooth is in its normal position, the strain or force necessary to retain it in position is almost wholly borne by the bolts E' and D, thus relieving the spring of any undue strain or work. When an obstruction which causes the tooth to yield is met with, the spring is called into action and allows the tooth to yield, and then returns it to its original position after the obstruction has been passed.

The vertical adjustment of the tooth rela-

tively to the drag-bar and the adjustment of the tension of the spring are important features, as, by simply turning the eccentric roller, the machine is adapted and adjusted for any kind of soil.

By locating the spring in the manner shown and described, it is situated out of the way and is not liable to become broken in the use of the machine.

As it is evident that many slight changes in the form, construction, and relative arrangement of the different parts of my improvement might be resorted to without departing from the spirit of my invention, I would have it understood that I do not restrict myself to the particular construction, form, and arrangement of parts shown and described; but,

Having fully described my invention, what I claim as new, and desire to secure by Letters Patent, is—

1. The combination, with a drag-bar, tooth, and link connecting the tooth and drag-bar, of locking-bars pivoted to the tooth and drag-bar, a spring engaging the locking-bar, and an adjustable support for one end of the spring, substantially as set forth.

2. The combination, with the drag-bar, tooth, and links connecting the tooth and drag-bar, of locking-bars pivotally connecting the upper end of the tooth and the drag-bar, and a spring pivotally connected at one end with the locking-bars, and its opposite end supported on an eccentric-roller bearing, substantially as set forth.

3. The combination, with a yielding tooth and spring, of an eccentric roller with which one end of the spring engages, substantially as set forth.

4. The combination, with a tooth pivotally connected to links attached to the drag-bar, of an eccentric roller and a spring having a forked end that engages said roller, substantially as set forth.

5. The combination, with a drag-bar composed of side pieces connected together, a tooth and links pivoted to the tooth and to the drag-bar, of locking-bars pivoted between the side pieces of the drag-bar and to the upper end of the tooth, and a spring situated between the side pieces of the drag-bar, one end of the spring engaging the locking-bars and the other end engaging an adjustable support, substantially as set forth.

6. The combination, with a tooth secured to a drag-bar, of an eccentric abutment for the upper end of the tooth, whereby the angle formed by the line of draft and line of connection is varied, substantially as set forth.

In testimony whereof I have signed this specification in the presence of two subscribing witnesses.

ANDREW G. ANDERSON.
